UNITED STATES PATENT OFFICE.

WILLIAM L. DENCH, OF PELHAM, NEW YORK, ASSIGNOR TO ELLIOTT-FISHER COMPANY, OF NEW YORK, N. Y., A CORPORATION OF DELAWARE.

VARIABLE AUTOMATIC SPACING MECHANISM FOR COMBINED TYPE-WRITING AND ADDING MACHINES.

No. 927,838.

Specification of Letters Patent.

Patented July 13, 1908.

Application filed February 12, 1908. Serial No. 415,469.

To all whom it may concern:

Be it known that I, WILLIAM L. DENCH, a citizen of the United States, residing at Pelham, in the county of Westchester and State 5 of New York, have invented certain new and useful Improvements in Variable Automatic Spacing Mechanism for Combined Type-Writing and Adding Machines, of which the following is a specification.

10 My present invention relates to spacing mechanism for machines of that class which embrace a traveling carriage movable to different positions to space printed characters or to select different denominations, as for 15 instance of an adding mechanism. Type-writing machines, computing machines, and combined typewriting and computing machines are all embraced within the class mentioned, and my invention may be considered more specifically as relating to automatic spacing mechanism for combined typewriters and adders.

The machine for the equipment of which the mechanism constituting my invention 25 has been devised is the Elliott-Fisher machine of commerce: This machine is what is known as a flat platen typewriter equipped with adding mechanism operated from the numeral keys to add a column of numbers 30 as the latter are printed by the typewriter. As is well understood in the art, the typewriter carriage advances step-by-step to 35 space the characters printed, and when numbers of comparatively large denominations are printed, it is customary to leave 40 spaces or print commas between groups of digits. So also, when the numbers printed represent money values, a decimal space is left or a decimal point is printed. In order 45 to avoid the loss of time incidental to the printing of the decimal or commas, or the operation of a space key to space the carriage over the comma or decimal spaces, it has been proposed to provide automatic 50 spacing mechanism which will effect an exaggerated operation of the typewriter escapement when a comma or decimal space is reached, thus causing the carriage, without attention on the part of the operator, 55 to space two spaces upon the release of the key after printing a character to the left of a given comma or decimal position. Such spacing mechanism is entirely efficient for the performance of its intended function, but the preferences of certain operators and

the demands of certain classes of work make it desirable to vary the condition of the spacing mechanism so that the machine will automatically space over both comma and decimal points where speed of operation is 60 the primary consideration, or automatically space over the decimal point alone when it is desired to print the commas, or entirely eliminate the automatic spacing feature, in order that both the commas and decimal 65 points may be printed when speed of operation is subordinate to the desire to have all of the usual punctuation marks appear in the printed column.

Having these considerations in mind, the 70 object of my invention is to produce a spacing mechanism adapted for the equipment of a machine of the character specified and capable of securing the recited variations of spacing conditions, to-wit, no automatic 75 spacing, automatic spacing at the decimal point alone, or automatic spacing at both the decimal and comma points.

To the accomplishment of this primary 80 object and others subordinate thereto, the preferred embodiment of the invention resides in that construction and arrangement of parts to be hereinafter described, illustrated in the accompanying drawings, and succinctly defined in the appended claims. 85

In said drawings Figure 1 is a sectional elevation of so much of an Elliott-Fisher billing machine as is necessary to show the application of my spacing mechanism thereto. Fig. 2 is a rear elevation of the upper portion of a 90 machine equipped with my invention. Fig. 3 is a perspective view of the spacing mechanism and associated parts detached. Fig. 4 is a sectional view of a portion of the carriage casing showing the spacing mechanism 95 in plan, the two extreme positions of the trip arm being indicated in dotted lines. Fig. 5 is a vertical section through the carriage casing, showing the spacing mechanism in elevation and indicating in dotted lines the extreme positions of the trip arm and the space key, respectively. Fig. 6 is a sectional view 100 showing a portion of the automatic key connecting mechanism. Fig. 7 is a vertical sectional view through the carriage of the typewriter, showing the carriage feeding mechanism or escapement and certain of the elements of the automatic spacing mechanism. Fig. 8 is a detail view of the setting key for 105 the spacing mechanism. Fig. 9 is a detail 110

perspective view of the setting lever. Fig. 10 is a detail view of the rear end of the rock shaft and its associated arm. Fig. 11 is a front elevation of the register equipped with 5 comma trips and a decimal trip. Fig. 12 is a bottom plan view of the same, and Fig. 13 is an essentially diagrammatic view indicating the relation of the trip arm to the several trips and designed more particularly to indicate the three paths of movement of the trip arm in the three set positions of the latter.

Each part is indicated by its appropriate reference character, wherever shown.

The Elliott-Fisher billing machine illustrated in the drawings comprises a flat platen 1 upon which the work sheet is supported and over which travels longitudinally thereof, for line spacing, a machine frame 2 which in turn supports a carriage 3 movable transversely of the platen to letter space the writing. Mounted on and movable with the carriage 3 is a downwardly acting printing mechanism including type arms 4 operated through suitable intermediate connections 20 by letter and numeral keys 5 and 6.

The carriage 3 is propelled to the right by carriage propelling mechanism including spring drums, not shown, connected to the carriage by flexible tapes 7, one of which is indicated in Fig. 2. The step-by-step movement of the carriage for letter spacing is controlled by carriage feeding mechanism operated from the typewriter keys in a manner well understood in the art (see Fig. 7) and 30 including a carriage feed spindle 8 geared to the frame 2, as indicated at 8^a, and controlled by an escapement which includes a ratchet wheel 9 fixed to the spindle 8 and co-operating with two dogs 10 and 11 connected by 35 links 12 and 13 to a vibrator 14, which is in turn connected by a link 15 to an arm of a rock shaft 16 arranged to be rocked by slides 17, which are in turn operated by key yokes 18 mounted in the carriage of the typewriter 40 and operated, as any given key reaches the downward limit of its movement, to effect the rocking of the shaft 16 and thus swing the vibrator 14, all as fully described and shown in Patent No. 765,861 to John A. Smith.

50 It will be noted that the dog 10 normally engages the escapement wheel 9 and thus holds the carriage against movement. Upon the depression of a key, the dogs are simultaneously moved in opposite directions, the dog 11 reaching its engaging position before the carriage is released and permitting only sufficient movement of the wheel 9 to insure the engagement of the dog 10 with the next succeeding tooth of the wheel when the dogs are again reversed by the action of a retracting spring 19 upon the release of the key. Therefore, as the key is depressed, there is no appreciable movement of the carriage, but upon the release of the key the dog 11 moves 55 out of engagement with the wheel 9 thus

permitting the latter to rotate the distance of one letter space or one tooth of the ratchet 9 before the carriage is arrested by the re-engagement of the dog 10 with the ratchet.

The adding mechanism.—The adding mechanism, which is combined with the typewriting machine, includes a totalizer, register, or computing device 20 adjustably mounted on the frame 2 and located in rear of the upper portion of the carriage 3 (see Fig. 1). The register 20 is of well known construction and includes a series of denominational members or number wheels 21 arranged in line and equipped with suitable carrying mechanism whereby the value accumulated upon any wheel will be transferred or carried to the wheel of next higher order. The register constitutes the relatively fixed unit of the adding mechanism, which latter also embraces a relatively movable unit in the form of actuating mechanism which travels with the typewriter carriage 3 and is presented by the movement of such carriage to successive number wheels. Thus upon the depression of any numeral key of the typewriter to print a digit in a given denominational position of the adding field or column, the number wheel of corresponding denomination will be moved a number of increments corresponding to the value of the printed digit, thereby accumulating the value of the digit in the register, simultaneously with the printing thereof.

The actuating mechanism embraces a master wheel 22 and suitable differential connections between the master wheel and the several numeral keys 6, the connections being so proportioned that each numeral key will move the master wheel a distance proportionate to the value of said key.

100 It is thought to be unnecessary to specifically describe either the register or its operating connections, but for a more complete disclosure of these mechanisms, attention is directed to Patents Nos. 825,469 and 829,971 to Laganke and Smith.

The variable automatic spacing mechanism.—The Elliott-Fisher machine is extensively used for the computation of money values and includes in its organization automatic spacing mechanism arranged to cause the carriage to skip over a predetermined point, as for instance a decimal space, upon the release of a key after the printing of a digit at the left of such space or point. One form of such mechanism is disclosed in Patent No. 820,879 to Laganke and Smith, but a form more nearly approximating that which is disclosed in the accompanying drawings is shown in the copending application of John A. Smith, No. 390,360.

115 Depending from the casing of the register 20 is a decimal spacing trip 28 in the form of a pointed tooth disposed in the path of a trip arm 29 having a pointed tooth 29^a which, 120

when the decimal space is reached by the carriage, engages and passes under the trip 28. The trip arm 29 is secured to the outer end of a rock shaft 30, which is rotatable and 5 longitudinally movable in a bearing sleeve 31 projecting through the back wall 3^b of the carriage casing, see Figs. 1, 3, 4, 5 and 7.

Adjacent to the inner end of the rock shaft 30 is secured an arm 32 the free end of which 10 is disposed over the laterally disposed end or lug 33 of a dog retarding lever 34. The lever 34 is fulcrumed intermediate of its ends upon the back wall of the carriage casing and is extended under the pin 35 projecting laterally 15 from the free end of the dog 10.

We have already seen that the letter space advance of the carriage is effected while the dog 10 is moving back to engage the next succeeding tooth of the ratchet, and it will 20 therefore be obvious that if this movement of the dog to its engaging position is momentarily retarded, the ratchet will be permitted to move the distance of two teeth instead of one before it is engaged and the carriage 25 rested by the dog. The parts just described are designed to effect this momentary retardation of the dog 10 so that as the carriage moves from the units position it will advance 30 a double space or the distance of two normal letter space movements, so as to cause the printing point to pass directly from the units to the tenths position and skip over the decimal space. It will be seen that when the trip arm 29 engages the decimal spacing trip 35 28, said arm will be slightly depressed, thus rocking the shaft 30 and depressing the arm 32, which in turn depresses the left hand end of the lever 34 and causes the right hand end of said lever to rise and thus, by engagement 40 with the pin 35, to retard the movement of the dog 10 toward its engaging position, the retardation being obviously momentary because of the very brief or momentary engagement of the trip 28 with the pointed tooth 45 29^a of the trip arm.

It is sometimes desirable to render the decimal spacing mechanism inoperative, particularly in writing ordinary matter across that area which may be used as the adding 50 field, for instance when the computing device is entirely out of use or when it is desired to write matter across the sheet above or below a column of numbers which are to be or have been added. In order to render the decimal 55 spacing mechanism operative or inoperative, the shaft 30 is made longitudinally movable, as stated, in order to permit the same to be shifted back to bring the trip arm 29 into co-operative relation with the trip 28 or forward 60 to present the trip arm out of co-operative relation with said trip. These two positions of the trip arm 29 are the positions *a*, *b*, Figs. 4, 5 and 13, it being obvious that when the trip arm is in position *a*, its advance with the 65 typewriter carriage will cause it to traverse

a path in advance of and unobstructed by the decimal trip 28, whereas when the trip arm 29 is shifted rearwardly to position *b*, it will traverse a path obstructed by the trip 28 which will thus cause automatic spacing of 70 the carriage over the decimal space. The trip arm 29 is "set" in its different positions by means of a key 36 (see Figs. 2, 3 and 8) having a shank 37 pivotally mounted on a bearing bracket 38 secured to the cover-plate 75 of the carriage. The lower end of the shank 37 is provided with a tongue 39 which engages the angular forked extremity 40 of a setting lever 41 fulcrumed intermediate of its ends, as indicated at 42, to a bracket 43 secured to the wall 3^b of the carriage. The opposite end of the lever 41 is turned to vertical position, as shown in Fig. 9, and is provided with a fork 44 engaging a reduced portion 45 of the rock shaft 30. It will thus be seen 80 that by tilting the space key 36 in one direction the lever 41 will be swung to shift the shaft 30 longitudinally and thus present the trip arm 29 in operative position. Similarly, by tilting the key 36 in the opposite direction, the arm 30 will be withdrawn to its ineffective or inoperative position. Therefore, 85 by manipulating the key 36, the operator may determine whether or not the automatic spacing mechanism will operate when the 90 tooth 29^a of the arm 29 reaches the decimal spacing trip 28.

The provision for both comma and decimal spacing.—The mechanism substantially as thus far described is disclosed in the application of John A. Smith, hereinbefore identified, but it will be noted that thus far we have only considered the mechanism as a means for securing or eliminating automatic spacing. In accordance with my invention, 105 however, the decimal trip 28 is made of double width from front to back, as best shown in Fig. 13, and in line with the rear portion of this trip the register is equipped with suitably spaced additional trips 45 and 46. 110 These trips being of only approximately one-half the width of the trip 28, are located in rear and outside of the path traversed by the trip arm when the latter is in position *b*. The additional trips 45 and 46 are located in 115 positions appropriate to the comma spaces of the column, so that, if engaged by the trip arm 29, during the movement of the carriage, the latter will be spaced over the comma spaces as well as the decimal space. To provide for this engagement of the trip arm with all of the trips, it is merely necessary to so proportion the parts which support and shift the trip arm that the latter may be shifted to any one of three positions instead of to either 120 of two positions, as is disclosed in the Smith application. Thus in accordance with my present invention, the rock shaft 30 is lengthened somewhat to accommodate the additional movement, and the end 33 of the 125

retarding lever 34 is of sufficient length to remain in engagement with the arm 31 in each of the three set positions of said arm. Similarly, the key 36 is movable to either of three positions, as shown in Fig. 5, so that the shaft 30 may be shifted endwise to present the trip arm 29 in position *a* or *b*, as already described, or in a still more rearward position *c*. In this third position the trip arm 10 will traverse a path obstructed by all three of the trips, to-wit, the comma trips 45 and 46, and the decimal trip 28. Thus it will appear that by the simple manipulation of the key 36 to either of its three set positions, the 15 operator may establish any one of the three desirable conditions of the spacing mechanism, that is to say, this mechanism may be set in inoperative condition when no automatic spacing is desired (position *a*), or in 20 condition to secure decimal spacing alone (position *b*), or in condition to secure both comma and decimal spacing (position *c*). It should be understood, however, that it is within the purview of the invention to increase or diminish the number of trips or to 25 increase the number of set positions of the trip arm for the purpose of causing the latter to move in paths obstructed by selected trips.

The retention of the setting key in its several "set" positions may be effected by the frictional resistance of the parts or by a detent of any desired form coacting with the key or some other element of the associated mechanism. Before concluding, attention 30 may be directed to the fact that the spacing mechanism coacts with the escapement of the carriage feeding mechanism to exaggerate the normal carriage movement at a predetermined point or at predetermined 35 points and that its operation is entirely independent of any operation of the carriage release key. Therefore, the escapement of a machine equipped in accordance with my invention is operated normally to effect a letter space movement of the carriage by the 40 operation of the letter and numeral keys or is operative to release the carriage and permit free movement thereof by the operation of the release key and is operative to effect 45 exaggerated spacing at predetermined points, as for instance the comma and decimal 50 points, by the automatic operation of the several mechanisms hereinbefore described. Attention is also directed to the fact that the 55 spacing mechanism embraces two coacting units, to-wit, the series of trips and the trip arm, which are brought into engagement by the movement of the carriage and which are relatively variable to attain different spacing 60 conditions by the manipulation of a setting key.

It is thought from the foregoing, the construction and operation of my variable spacing mechanism will be fully understood, but 65 while the illustrated embodiment of the in-

vention appears at this time to be preferable, I reserve the right to effect such changes, modifications and variations of the illustrated structure, as may come fairly within the scope of the protection prayed. 70

What I claim is:—

1. The combination with a carriage and means for effecting a uniform step-by-step movement thereof, of automatic spacing mechanism operative to cause exaggerated 75 movement of the carriage at predetermined points in its travel, said spacing mechanism being variable to predetermine the number of points at which said spacing mechanism shall operate. 80

2. The combination with a carriage and means for effecting a uniform step-by-step movement thereof, of spacing mechanism brought into action by the movement of the carriage to exaggerate the normal movement 85 of the latter, said spacing mechanism including a plurality of devices relatively adjustable to determine the number of times the spacing mechanism will operate during a single traverse of the carriage. 90

3. The combination with a carriage and means for effecting a normal uniform step-by-step movement thereof, of spacing mechanism including a series of devices and a single device adapted to be brought into engagement with the series of devices successively by the movement of the carriage to exaggerate the normal carriage movement at successive points in the carriage travel, said devices being relatively adjustable to different set 100 positions to predetermine the number of points at which exaggerated spacing will be effected. 95

4. The combination with a carriage and means for effecting a normal step-by-step movement thereof, of spacing mechanism co-operating with said means to exaggerate the normal movement of the carriage, said spacing mechanism including two units relatively movable by the carriage into coactive relation, one unit including a series of devices and the other unit including a single device adapted to coact successively with each of the devices first named and one of said units being adjustable to different set positions to 110 determine the extent of coaction between the respective units. 115

5. The combination with a carriage and means for effecting a normal step-by-step movement thereof, of spacing mechanism 120 adapted to co-operate with said means to exaggerate the normal carriage movement, said spacing mechanism including two units, one mounted on the carriage and the other relatively stationary, one unit including a series of devices located at different points and the other unit including a single device, and means for independently adjusting a device of one unit into and out of interfering relation with a device of the other unit. 125

6. In a typewriting machine, the combination with a carriage, of an escapement controlling the normal step-by-step advance of said carriage, release mechanism arranged to operate the escapement to permit free movement of the carriage, and spacing mechanism independent of the release mechanism and acting automatically at given points in the movement of the carriage to exaggerate the extent of the carriage movement by coöperation with the escapement, said spacing mechanism being variable to determine the number of points at which the carriage movement will be exaggerated in a single traverse of the machine by said carriage. 65
7. In a typewriting machine, the combination with a carriage, of an escapement controlling the normal step-by-step advance of said carriage, release mechanism arranged to operate the escapement to permit free movement of the carriage, and spacing mechanism independent of the release mechanism and acting automatically at given points in the movement of the carriage to exaggerate the extent of the carriage movement by coöperation with the escapement, said spacing mechanism including two coacting units one of which is adjustable to operative or inoperative position and is also adjustable to different operative positions to determine the number of points at which the carriage movement will be exaggerated in a single traverse of the machine by said carriage. 70
8. In a typewriting machine, the combination with a carriage, of an escapement controlling the normal step-by-step advance of said carriage, release mechanism arranged to operate the escapement to permit free movement of the carriage, and spacing mechanism independent of the release mechanism and acting automatically at given points in the movement of the carriage to exaggerate the extent of the carriage movement by coöperation with the escapement, said spacing mechanism being variable to determine whether or not said mechanism shall operate and also to determine the number of times the carriage movement will be exaggerated in a single traverse of the machine by the carriage. 75
9. In a typewriting machine, the combination with a carriage, of an escapement controlling the normal step-by-step advance of said carriage, release mechanism arranged to operate the escapement to permit free movement of the carriage, and spacing mechanism independent of the release mechanism and acting automatically at given points in the movement of the carriage to exaggerate the extent of the carriage movement by coöperation with the escapement, said spacing mechanism including a plurality of devices and a single device adapted to coact therewith, one of said devices being adjustable into and out of operative position. 80
10. In a typewriting machine, the combination with a carriage, of an escapement controlling the normal step-by-step advance of said carriage, release mechanism arranged to operate the escapement to permit free movement of the carriage, and spacing mechanism independent of the release mechanism and acting automatically at given points in the movement of the carriage to exaggerate the extent of the carriage movement by coöperation with the escapement, said spacing mechanism including two coacting units one of which is adjustable to operative or inoperative position and is also adjustable to different operative positions to determine the number of points at which the carriage movement will be exaggerated in a single traverse of the machine by said carriage. 85
11. In a typewriting machine, the combination with a carriage, of an escapement controlling the normal step-by-step advance of said carriage, release mechanism arranged to operate the escapement to permit free movement of the carriage, and spacing mechanism independent of the release mechanism and acting automatically at given points in the movement of the carriage to exaggerate the extent of the carriage movement by coöperation with the escapement, said spacing mechanism including a plurality of trips and a trip arm adapted to coact therewith and means for moving the trip arm into and out of operative position and to either of several operative positions, substantially as and for the purpose specified. 90
12. In a typewriting machine, the combination with a carriage, of an escapement controlling the normal step-by-step advance of said carriage, release mechanism arranged to operate the escapement to permit free movement of the carriage, and spacing mechanism independent of the release mechanism and acting automatically at given points in the movement of the carriage to exaggerate the extent of the carriage movement by coöperation with the escapement, said spacing mechanism including a plurality of devices located in different planes and a coacting device adjustable to different set positions corresponding to said planes. 95
13. In a typewriting machine, the combination with a carriage, of an escapement controlling the normal step-by-step advance of said carriage, release mechanism arranged to operate the escapement to permit free movement of the carriage, and spacing mechanism independent of the release mechanism and acting automatically at given points in the movement of the carriage to exaggerate the extent of the carriage movement by coöperation with the escapement, said spacing mechanism including a plurality of trips and a

trip arm adjustable into interfering relation with certain or all of the trips or with none of said trips, as desired.

14. In a typewriting machine, the combination with a carriage, of an escapement controlling the normal step-by-step advance of said carriage, release mechanism arranged to operate the escapement to permit free movement of the carriage, spacing mechanism independent of the release mechanism and acting automatically at given points in the movement of the carriage to exaggerate the extent of the carriage movement by co-operation with the escapement, said spacing mechanism including two units adapted to be brought into engagement by the movement of the carriage, one of said units including a plurality of trips and the other unit including a member coacting with said trips, and means for adjusting one of the units to different set positions to vary the number of trips engaged by the member during a traverse of the machine by the carriage.

15. In a typewriting machine, the combination with a carriage and means for effecting the normal step-by-step advance of said carriage, of spacing mechanism automatically operated by the movement of the carriage to exaggerate the normal carriage movement, said spacing mechanism including coacting devices, and setting means operative to vary the relation of said devices to determine whether or not the spacing mechanism shall operate and to vary the number of points at which the carriage movement will be exaggerated in a traverse of the machine by said carriage.

16. In a typewriting machine, the combination with a carriage and means for effecting the normal step-by-step movement thereof, of spacing mechanism automatically operated by the movement of the carriage to exaggerate the normal movement thereof, said spacing mechanism including a plurality of devices and a single device successively co-operating with said devices, and a setting key operative to vary the relation of the several coactive devices, to select or determine the number of said first named devices with which the single devices will co-act.

17. The combination with a typewriting machine including a frame, carriage, and means for effecting the normal step-by-step advance of the carriage, of spacing mechanism coacting with said means and brought into action by the movement of the carriage to exaggerate the normal movement thereof, said spacing mechanism including a plurality of said trips, a trip arm, and means for setting the trip arm in different operative positions and also in an inoperative position.

18. In a typewriter, the combination with the frame, carriage, and carriage feeding mechanism, of spacing mechanism coacting with the feeding mechanism and brought into

action by the movement of the carriage to exaggerate the normal movement thereof, said spacing mechanism including a plurality of trips mounted on the frame, a trip arm mounted on the carriage, and a setting key arranged to move the trip arm into and out of operative position and also the different operative positions to vary the number of trips engaged by said arm.

19. In a combined typewriting and adding machine, the combination with a typewriter including a carriage, an escapement controlling the normal step-by-step movement thereof, and printing mechanism including keys, arranged to operate the escapement, of an adding mechanism including a register, actuating mechanism therefor, and spacing mechanism automatically operated by the movement of the carriage and mounted in part on the register, said spacing mechanism being variable to determine the number of points at which said spacing mechanism will operate as the carriage is traversing the width of the adding field.

20. In a combined typewriting and adding machine, the combination with a typewriter including a carriage, an escapement controlling the normal step-by-step movement thereof, and printing mechanism including keys arranged to operate the escapement, of an adding mechanism including a register, and actuating means therefor having its denominational relation controlled by the movement of the typewriter carriage, and automatic spacing mechanism coacting with the escapement to exaggerate the carriage movement for the purpose of causing the latter to skip over comma and decimal spaces, said spacing mechanism being variable to determine the number of points over which the carriage will be automatically spaced by the spacing mechanism during a given traverse of the adding field.

21. In a combined typewriting and adding machine, the combination with a typewriter including a carriage, an escapement controlling the normal step-by-step advance thereof, and printing mechanism including keys arranged to operate the escapement, of an adding mechanism including a register and actuating mechanism therefor having their denominational relation controlled by the movement of the typewriter carriage, and automatic spacing mechanism brought into action by the movement of the typewriter carriage and coacting with the escapement to space the carriage over a plurality of points within the adding field, as for instance the decimal and comma points, said spacing mechanism being variable to determine whether or not it will operate to automatically space the carriage during a traverse of the adding field and also to determine the number of points at which it will operate during such traverse.

22. In a combined typewriting and adding machine, the combination with a typewriter including a carriage, an escapement controlling the normal step-by-step advance thereof, and printing mechanism including keys arranged to operate the escapement, of an adding mechanism including a register and actuating mechanism therefor having their denominational relation controlled by
- 5 the movement of the typewriter carriage, automatic spacing mechanism brought into action by the movement of the typewriter carriage and coacting with the escapement to space the carriage over a plurality of
- 10 points within the adding field, as for instance the decimal and comma points, said spacing mechanism being variable to determine whether or not it will operate to automatically space the carriage during a traverse of the adding field and also to determine the number of points at which it will operate during such traverse, and a setting key for varying the spacing mechanism.
23. The combination with a carriage and
- 25 means for effecting a uniform step-by-step
- movement thereof, of variable automatic spacing mechanism operative to cause exaggerated movement of the carriage at a number of predetermined points in its travel, said spacing mechanism including a setting key movable to different positions to vary the points at which the exaggerated spacing will occur.
24. The combination with a carriage and means for effecting a uniform step-by-step movement thereof, of automatic spacing mechanism operative to cause exaggerated movement of the carriage at a number of predetermined points in its travel, said spacing mechanism including a setting key and means variable by said setting key to select or determine the point or points in the carriage travel at which exaggerated movement of said carriage will be effected.

In testimony whereof I affix my signature in presence of two witnesses.
